Attorney

UNITED STATES PATENT OFFICE.

MILES F. DEACH, OF OAKLAND, CALIFORNIA.

ELECTRIC-LAMP FIXTURE.

Application filed October 27, 1920, Serial No. 419,981. Renewed February 7, 1923.

To all whom it may concern:

Be it known that I, MILES F. DEACH, a citizen of the United States, residing at Oakland, in the county of Alameda and State of California, have invented certain new and useful Improvements in Electric-Lamp Fixtures, of which the following is a specification.

My invention is an improved electric lamp fixture.

Referring to the annexed drawing in which my invention is illustrated and which forms a part of this specification,

Figure 1 is an elevation of my fixture and an electric lamp mounted thereon.

Figure 2 is a view similar to Fig. 1 taken at right angles thereto.

Figure 3 is a vertical section of the fixture taken on line 3—3 of Figure 2.

Figure 4 is a sectional view of the clamping rings taken on line 4—4 of Figure 3.

Figure 5 is an inside view of one of the clamping members.

In the drawing, 1 indicates a base and 2 a cylindrical standard secured in said base. A sleeve 3 fits over the top of said standard, a portion 4 of the wall of the sleeve converging upwardly and resting on the top of the standard and supporting the sleeve 30 at the proper elevation on the standard so that the sleeve may turn on the standard. The lower end 5 of the sleeve 3 converges inwardly into frictional engagement with the standard 2 to normally prevent turning 35 of the sleeve on the standard and is slit upwardly at 6 in several places to allow the parts between the slits to yield so that the sleeve may be turned by the application of a little force thereto. The upper end of the 40 sleeve 3 is split downwardly, forming two ears 7 and 8 upstanding from the converging portion 4 of the sleeve, said ears having central openings 9 and 10 to receive a screw 11, the head 12 of which engages the ear 8.

45 A butterfly nut 13 screws on the screw 11 against the ear 7. A pair of clamping members 14 and 15 are interposed between the ears 7 and 8. The clamping member 14 comprises an end wall 16 provided with an opening 17 through which extends screw 11, and an annular flange 18 extending inwardly from said end wall. The clamping member 15 comprises an end wall 20 provided with an opening 21 through which extends the screw 11 and an annular flange 22 extending inwardly from said end wall. The

flange 18 of clamping member 14 is provided with two semi-circular notches 25 and 26 in its inner edge arranged opposite each other. The flange 22 of the clamping member 15 is provided with two semi-circular notches 27 and 28 in its inner edge arranged opposite each other so as to register respectively with the notches 25 and 26. A tube 30 extends through the clamping members 14 and 15, fitting in the notches 25 and 27 and 26 and 28, on one end of which tube is mounted an electric lamp 31, the leads 32 and 33 of the lamp extending through said tube. The clamping members 14 and 15 together with the tube 30 and the lamp 31 may be turned in a vertical plane on the screw 11 and clamped at any angle upon tightening the butterfly nut 13, which draws the ears 7 and 8 against the clamping members 14 and 15 and the notches 25 and 27 and 26 and 28 tightly against the tube 30. The lamp may be turned in a horizontal plane, the split lower end 5 of the tube 3 allowing the sleeve to turn on the standard 2. The tube 30 may be extended through the notches 25 and 27, and the lamp may also be rotated about said tubes.

Having described my invention, I claim:

1. A lamp fixture including a base, a standard mounted on said base, a sleeve turnably mounted and resting freely on said standard, the lower end of said sleeve being split and converging into frictional engagement with said standard, a tube mounted on the upper end of said sleeve, and a lamp on the end of said tube.

2. A lamp fixture including a base, a standard mounted on said base, a sleeve turnably mounted on said standard, the wall of said sleeve converging upwardly and resting on the top of said standard to support the sleeve on the standard, a lamp and means for mounting said lamp on the upper end of said sleeve.

3. A lamp fixture including a base, a standard on said base, a sleeve turnably mounted on said standard, a pair of upstanding ears formed integrally on the upper end of said sleeve, a pair of clamp members between said ears, a screw extending through said ears and said clamp members on which screw said clamp members are adapted to turn, a rod between said clamp members, the head of said screw engaging the outside of one of said ears, and a butterfly nut on the other end of said screw for

engaging the other ear to draw said ears against said clamp members and said clamp members against said rod to clamp said rod and lamp at any angle.

- 5 4. A lamp fixture including a base, a standard on said base, a sleeve turnably mounted on said standard, a pair of up-standing ears formed integrally on said sleeve, a pair of clamp members between 10 said ears, each clamp member including an end wall and an inturned annular flange in the inner edge of which flanges are registering notches, a rod extending between said clamp members, a lamp on said rod, a screw

extending through said ears and the end 15 walls of said clamp members on which screw said members may turn, the head of said screw engaging the outside of one ear, and a butterfly nut on the other end of said screw engaging the other ear to draw said ears 20 against the end walls of said clamp members and the notches of said clamp members against said rod to clamp the lamp at any angle.

In testimony whereof I affix my signature.

MILES F. DEACH.
